FABRIC FOR GARMENT EDGING

Norman E. Randall, Shannock, R. I., assignor to
Columbia Narrow Fabric Company, a voluntary
association of Rhode Island

Application March 6, 1941, Serial No. 331,979

1 Claim. (Cl. 139—384)

This invention relates to a length of fabric for use as an edging for a garment, particularly a girdle, and to the girdle formed with such edging.

It is well known in the use of girdles that the upper edge of the girdle tends to bend over, especially when the wearer is fat, and if a girdle so bends or rolls at its upper edge, the girdle will stay in this bent or rolled condition until it is taken off. Various attempts have been made to stiffen the upper edge of the girdle, such, for instance, as placing thereon a narrow edge consisting of fabric in which there has been provided pockets which receive short, steel stays extending vertically upward in the garment at its upper edge when worn for holding the garment in its desired position and to prevent this rolling or bending at the upper edge. The formation of a fabric in this manner is expensive. The positioning of steel stays is expensive, and the results are not comfortable and therefore not wholly desirable. Other means of stiffening have been attempted such, for instance, as providing vertically-extending ribs along the upper edge of the fabric, by manipulation of the warp yarns to provide a cord effect, or a bunch extending across the fabric in the form of a rib; and while such arrangements do somewhat stiffen, the stiffening is not sufficient to be effective in all cases, and when once bent lacks sufficient inherent tendency to return to a straight condition.

One of the objects of this invention is to avoid the use of steel stays or pockets or ribs formed from the warp yarns in a fabric edge, but to utilize a filling yarn to provide the stiffness desired.

Another object of the invention is to provide a fabric which will be freely flexible circularly of the garment or longitudinally of the fabric but will be stiff against bending vertically of the garment or across the stiffer yarns which are placed in the fabric.

Another object of the invention is to utilize a filling which itself is flexible although stiff when a plurality are placed together in parallel relation to resist an attempt to be rolled or doubled sharp upon itself.

With these and other objects in view, the invention consists of certain novel features of construction, as will be more fully described, and particularly pointed out in the appended claim.

In the accompanying drawing:

Fig. 1 is a perspective view of the woven strip embodying my invention;

Fig. 2 is a sectional view of a fragmental por-

tion of the garment and my edge fabric attached thereto;

Fig. 3 is a detailed view illustrating the weave formation of the fabric shown in Fig. 1;

Fig. 4 is a view of the yarns in enlarged formation, showing the crossings of the yarn for their interlacings one with another; and

Fig. 5 is a view of the completed girdle.

I have illustrated my invention in a woven fabric in which the filling and warp yarns are substantially right angularly disposed, although there may be other forms of interlacing relatively flexible and stiff yarns for the carrying out of this invention. I have also illustrated my invention as primarily used upon girdles or women's undergarments. The fabric which I provide is in strip form and usually between one and two inches wide and of indefinite length, woven on a narrow fabric loom. The proper length to be circularly applied to the upper edge of the girdle will be cut from the strip of fabric and sewed to the top of the girdle.

The girdle is designated generally 10 in Fig. 2, and my top edging is designated generally 11 in Fig. 2 and is shown separately from the girdle in Fig. 1. This woven showing in Fig. 1 consists of a main body part 12 which is relatively stiff with two lips 13 and 14 which are relatively flexible and do not contain the stiffened material. These are formed together in the loom as a single integral woven structure.

The warp yarns which extend lengthwise of the material 11 consist of rubber yarns, designated 15, and fiber yarns, 16, such as rayon. Various arrangements for these yarns may be had but consist primarily in the body portion 12 of a two-rubber yarn alternating with a group of four rayon yarns across the fabric. The filling consists of a pick back and forth of a soft, flexible yarn 17, such as rayon, and a pick of a material 18 of much stiffer qualities than the yarn used in the warp or the filling 17.

The stiffer yarn 18 is located only in the body 12 of the fabric, while the rayon filling extends into and forms the edge portions or sewing lips 13 or 14. Although I have shown two lips or edge portions 13 and 14, a single edge or edge portion may in some cases suffice. To use some stiffer material as a filling to stiffen the fabric against bending across this filling performs the useful purpose which I desire in my fabric.

A filling yarn which has been found satisfactory as a stiffener material is "Saran" which is a synthetic material, apparently extruded, and in continuous lengths, which is placed on the

market by the Dow Chemical Company. This material is impervious to moisture and acids of the skin and does not deteriorate in sunlight. It may be made in various colors, and I will select a color which will blend harmoniously with the color of the rayon or other material which I use in the fabric edging or garment. The "Saran" is of a count or diameter which is relatively stiff as compared with rayon; and in the fabric which I provide this "Saran" is #P-4 or of a .017 diameter. From the above it will be apparent that I have provided one pick of "Saran" alternating with two picks of rayon, and this has been found to make a fabric which is sufficiently stiff when the parallel "Saran" picks are so arranged.

If stiffer fabric is desired, a larger number of picks of "Saran" will be placed in the fabric with fewer number of picks of rayon; or it may be the fabric may be entirely of "Saran" picks without any picks of rayon, if desired.

One weave structure is represented more fully in Fig. 3 in which the bracketed portions so designated are repeated and in which the vertical rows represent warps and the rows across represent filling. The solid portion represents that the warp where the solid portion occurs is above the filling, whereas the unfilled squares represent that the warp at this point is below the filling. The R's represent rubber warps, and the other

unlettered warps are spun rayon. The rayon and the "Saran" are labeled at the side edge for each of the fillings which are utilized in a stretch of one repeat.

5 In the edge or lip portions such as 13 and 14, instead of using rayon warps, I use cotton warps. This portion is shown in the repeat at the left hand edge of Fig. 3. In a conventional fabric I will repeat the bracketed part, designated 28, ten times for the unstiffened edge lip; while the bracketed portion of the body, designated 21, will be repeated twenty-four times (I have shown only three), there being body edgings E at another bracketed part, one being designated 22, which joins the body to the lips, while the other edge E is the salvage 23.

I claim:

An elastic edge for a garment comprising a fabric composed of relatively soft and flexible warp rubber and textile yarns and stiffer filling yarns of a synthetic plastic material interlaced to provide a fabric, said filling yarns being parallel and providing a fabric less flexible across the filling so disposed, said warp being freely extendible and flexible across the same about an axis parallel to the filling, and a pair of sewing lips of unstiffened material along one edge of the fabric, and woven integral with the stiffened portion of the fabric.

NORMAN E. RANDALL.
